UNITED STATES PATENT OFFICE.

ARTHUR R. SELDEN, OF ROCHESTER, NEW YORK.

LOOSE-LEAF BINDER.

1,398,306.

Specification of Letters Patent. Patented Nov. 29, 1921.

Application filed January 20, 1921. Serial No. 438,575.

To all whom it may concern:

Be it known that I, ARTHUR R. SELDEN, a citizen of the United States, and resident of Rochester, in the county of Monroe and 5 State of New York, have invented certain new and useful Improvements in Loose-Leaf Binders, of which the following is a specification.

The present invention relates to loose leaf 10 binders and an object thereof is to provide a binder employing two binder members, each of which has a cover hinged thereto and impaling projections, all combined with means for locking the members together. 15 A further object of the invention is to provide a binder having a locking means of novel construction which will hold two binder members in firm connection. A still further object of the invention is to provide 20 a leaf tightening means in connection with an impaling means which will prevent the movement of the leaves on the impaling means during the use of the binder. A further object of the invention is to provide 25 in connection with a locking means for holding two binder members together, a leaf tightening means controlled simultaneously with said locking means.

To these and other ends the invention 30 consists of certain parts and combination of parts, all of which will be hereinafter described, the novel features being pointed out in the appended claims.

In the drawings:

35 Figure 1 shows one of the binder members in front elevation and a fragment of one of the covers;

Fig. 2 is a section on the line 2—2, Fig. 1;

Fig. 3 is a front elevation of the other 40 binder member and shows also a fragment of the cover carried thereby;

Fig. 4 is an end view of the parts shown in Fig. 3;

Fig. 5 is a fragment of one of the leaves 45 showing the manner in which it is held by the impaling pins and the wedging means;

Fig. 6 is a plan view of the binder;

Fig. 7 is a view of the back of the binder;

Fig. 8 is a horizontal section on the line 50 8—8, Fig. 10;

Fig. 9 is an enlarged section on the line 9—9, Fig. 8;

Fig. 10 is an enlarged section on the line 10—10, Fig. 8;

55 Fig. 11 is a fragmentary sectional view of the two binder members; and

Fig. 12 is a detail view of one of the wedging members.

Referring more particularly to the drawings, 1 indicates one of the binder members 60 and 2 the other. Associated with these binder members is an impaling means consisting, in this instance, of pins 3 arranged on the binder member 1 and pins 4 arranged on the binder member 2. Each binder mem-

ber also has preferably a cover 5 hinged thereto at 6. Pockets or openings 7 may be provided in the binder members 1 and 2 in which the ends of the impaling pins 3 and 4 may extend as shown in Fig. 11. Each 70

binder member may also have a back casing 8 secured thereto and co-operating with the casing of the other member in order to provide a chamber in rear of the impaling means. The opposed faces of the binder 75

members 1 and 2 form rests or engaging surfaces for the leaves 9, each of which is, in this instance, provided with openings 10 for the impaling pins 3 and openings 11 for the impaling pins 4. It is apparent that the 80

leaves will be held between the two binder members when the latter are associated together and when the binder members are 85 separate, the leaves may be held on either binder member through the impaling pins on such member, thus permitting the leaves to be transferred one at a time from one binder member to the other and at the same time permitting the leaves on the two members to be brought together, due to the fact 90

that the openings in the leaves on any one member will be properly aligned for receiving the impaling pins on the other member.

It is desirable to provide some means for 95 securely holding the binder members together. With this purpose in view, the binder member 1 is provided with an elongated projection 12 preferably formed in one piece with the binder member 1 and pro-

jected laterally with reference to said binder member. This projection is adapted for co-operation with a clamp carried by the binder member 2. The clamp in the present 100 embodiment comprises two clamping members 13 and 14. The clamping member 13 is, in this instance, formed by a plate bent laterally from the strip of sheet metal pro-

viding the binder member 2. This plate has 105 spaced openings 15 therein formed by cutting the metal and to provide tongues 16 which are bent rearwardly from such plate.

The clamping member 14 is in the form of a 110

U shaped strip having its ends 17 extended through the openings 15 into parallel relation with the tongues 16. The projection 12 is received between the clamping members 13 and 14 and the member 14 is moved toward the member 13 to effect the clamping action.

Movement of the clamping member 14 relatively to the clamping member 13 may 10 be effected in any suitable manner. In this instance an operating rod 18 is provided which is mounted for movement, preferably rotary movement, in the tongues or projections 16 and has cam portions preferably in 15 the form of eccentric surfaces 19 operating in the arms 17 of the clamping member 14. Movement of the operating rod 18 in one direction moves the clamping member 14 toward the clamping member 13, while operation 20 of the rod in the opposite direction moves the clamping member 14 away from the clamping member 13. Longitudinal movement of the rod in the tongues 16 may be prevented by pins or projections 20 and 25 these pins also serve as stops for limiting the rotary movement of the rod in two directions. This rod lies in the chamber formed by the back casings 8 and has one end extending to the exterior of the casing and 30 provided with a slot 21 in which a coin or other instrument may be introduced for the purpose of effecting the turning of the rod 18.

Loose leaf binders which secure the leaves 35 through impaling means extending through openings in the leaves require that such openings be materially larger than the impaling projections in order to facilitate the movement of the leaves on such projections. 40 As a consequence, there is a tendency for the leaves to shift on the impaling projections or pins slightly and this interferes with the turning of the leaves one at a time. According to this invention, a leaf-tightening 45 means is provided which will shift the leaves in their planes into binding engagement with the impaling pins or projections.

This leaf-tightening means, in this instance, comprises two tightening devices 50 operating preferably with the edges of the sheets adjacent the impaling pins or projections 3 and 4. The sheets, in this instance, are formed with V-shaped notches 22 situated between the openings 10 and 11 and the 55 leaf tightening devices coöperate with the walls of these notches and force the leaves in their planes against the impaling pins 3 and 4, while at the same time preventing movement of the leaves in the direction of 60 the line of the centers of the openings 10 and 11. Each leaf-tightening device comprises, in this instance, a member 23 rigidly secured to the binder member 1 and a member 24 mounted on the binder member 2. The 65 member 24 is formed of sheet metal bent

between its ends to provide a wedge shaped portion 25 which may be readily introduced in the notches 22 of the leaves. The portion 25 is coextensive with the distance between the leaf engaging faces of the binder members 1 and 2, and the upper part thereof is notched at 26 to receive the member 23 while its lower end is provided with a guide pin or projection 27 adapted to operate in a slot 28 in the binder member 2, the member 23 operating to prevent leaves passing over the upper end of the portion 25 and the projection 27 operating to prevent leaves passing under the lower end of said portion. The ends of the metal piece forming the member 24 are bent into parallel relation at 29 to provide a projection, these ends having registering openings 30 through which the operating rod 18 extends. The operating rod has cam portions 31 thereon in the 80 form of eccentric surfaces which coöperate with the walls of the openings 30 in the two tightening devices. When the rod is turned in order to clamp the projection 12 between the clamping members 13 and 14, the members 24 of the tightening devices will be shifted outwardly into binding engagement with the walls of the notches 22 of the leaves 90. In this movement the members 24 are guided by the walls of slots 32 formed in the 95 supporting plate 13 of the binder member 2, such slots 32 being sufficiently large to permit play of the members 24 in order that the latter may be properly centered with respect to the notches 22. When the members 24 move into binding engagement with the walls of the notches 22, they shift the leaves in their planes into binding engagement with the impaling pins or posts 3 and 4 and this binding engagement together with the 100 binding engagement with the tapering faces 25 of the members 24 holds the leaves against any loose movement on the impaling pins or projections.

The shaft or operating rod 18 is preferably inclosed by a casing 33, in this instance, in the form of a channeled piece having its edges secured by screws 34 to the plate 13 above and below the shaft. By this arrangement, when the two binder members 115 are separated, the shaft and coöperating parts inclosed by the casing 33 are hidden from view.

In using the binder, assuming that the latter is closed or locked in the manner 120 shown in Fig. 9, the shaft 18 is turned to release the projection 12 from the clamping plates 13 and 14 and to move the members 24 of the leaf-tightening means inwardly, thus simultaneously unlocking the leaves 125 and the binder members. The upper binder member 1 may then be elevated with reference to the lower binder member 2 and as many leaves as desired removed with said upper binder member, due to the fact that 130

the latter has impaling pins thereon. The two members may then be laid flat on any table or support and the leaves transferred one at a time from one to the other. When 5 it is desired to assemble the binder, the impaling pins of each member are introduced into the openings of the leaves in the other member and after the members are properly coupled together the shaft 18 is turned, thus 10 clamping the projection 12 and at the same time locking the leaves through the movable leaf tightening members 24.

From the foregoing it will be seen that there has been provided a loose leaf binder 15 having two binder members, each of which has a cover hinged thereto and each of which has impaling projections extending therefrom. A novel means is provided for locking these binder members together, this 20 means preferably being in the form of a projection on one of the binder members operating between a movable and a fixed clamping member on the other binder member. The clamping members are controlled 25 by a shaft or rod lying to one side of the leaves and operable from the exterior of the binder. There has also been provided means for tightening the leaves in the binder to prevent any loose movement of the leaves 30 on the impaling means. This tightening means shifts the leaves in their plane into binding engagement with the impaling means and also interlocks with the leaves to prevent sidewise movement of the latter. 35 In this instance, this leaf tightening means is controlled by the operating member for locking the two binding members together.

What I claim as my invention and desire to secure by Letters Patent is:

40 1. A loose leaf binder comprising two binder members, impaling means carried by said members, means for locking said members together comprising a wide projection on one of said parts and two clamping jaws 45 on the other of said parts coöperating with opposite sides of the projection, one of said jaws being rigid with the part by which it is carried, the other being movable and both having arms projecting laterally 50 therefrom in one direction, and a cam member operating in said arms to effect the movement of the movable clamping jaw.

2. A loose leaf binder comprising two binder members, impaling means carried by 55 the members, and means for locking the members together comprising a projection on one of said members, two clamps carried by the other member, one of said clamps being rigid with the member and provided 60 with bearings and the other of said clamps having perforated arms at opposite ends, and a cam shaft turning in the bearings of the rigid member and coöperating with the arms of the movable member to effect the 65 movement of the latter.

3. A loose leaf binder comprising two binder members, impaling means carried by the members, a projection carried by one member, two clamping members carried by the other member, one of said clamping 70 members being fixed to such binding member and the other being movable, and a rotary rod coöperating with said clamping members for effecting their clamping action.

4. A loose leaf binder comprising two binder members, impaling means carried by the members, a projection carried by one of the members, a clamping member fixed to the other member to coöperate with one face of the projection, a U-shaped clamping 80 member mounted to coöperate with the opposite face of the projection and having its arms provided with openings, a rotary rod having cam portions operating in said openings to move the movable clamping member 85 toward and from the projection.

5. A loose leaf binder comprising two binder members, impaling means carried by the members, a projection carried by one member, a flange rigid with the other member and provided with two openings and two rearwardly extending perforated tongues, the portion of the flange between the openings acting as a clamping member, a U-shaped movable clamping member having arms extending through the said openings and provided with aligned openings, and a rotary rod turning in the perforated tongues and having cam portions operating in the openings of the arms of the U shaped 95 clamping member to move the movable clamping member toward and from the fixed clamping member. 100

6. A loose leaf binder comprising two binder members, leaf impaling means carried by the members, and leaf tightening means for shifting the leaves in their planes into binding engagement with the impaling means. 105

7. A loose leaf binder comprising two binder members, leaf impaling means carried by the members, and tightening means for engaging the edge of the leaves adjacent those portions penetrated by the impaling means, said impaling means and tightening 110 means being relatively movable to shift the leaves in their planes so that binding engagement with the leaves is maintained by the impaling and the tightening means. 115

8. A loose leaf binder comprising leaf impaling means, and tightening means for engaging the edge of the leaves adjacent the portions penetrated by the impaling means, said tightening means being movable relatively to the impaling means to shift the leaves in their planes into binding engagement with the impaling means. 120

9. A loose leaf binder comprising two binder members, leaf impaling means carried by the members, and wedge-shaped 130

- tightening devices arranged to coöperate with the walls of notches formed in those edges of the leaves adjacent the portions penetrated by the impaling means.
5. 10. A loose leaf binder comprising two binder members, leaf impaling means carried by said members, leaves through which said impaling means pass having V-shaped notches in the edges adjacent the portions 10 through which the impaling means pass, and wedge-shaped tightening devices movably mounted on one of the binder members and arranged to coöperate with the walls of the notches in the leaves.
15. 11. A loose leaf binder comprising two binder members, each of which has two impaling projections, the free ends of which coöperate with the other binder member, the projections on one binder member lying between the projections on the other binder member, leaves having perforations near one edge through which the impaling projections pass, said edge also having notches arranged beyond the innermost openings 25 and between the outermost openings, and tightening means coöperating with the walls of said notches.
12. A leaf for loose leaf binders having openings arranged in a line along one edge 30 for the reception of the impaling means, and having also V-shaped notches in said edge for engagement by tightening means.
13. A loose leaf binder comprising two binder members, leaf impaling means carried by the members, means for securing said binder members together, a tightening means for tightening the leaves on the impaling means, and a common operating member for the binder securing means and the 35 tightening means.
14. A loose leaf binder comprising two binder members, leaf impaling means carried by the members, a projection carried by one of the members, a clamp carried by the other member, a leaf tightening means for 40 tightening the leaves on the impaling means, and a common operating member for the clamping means and the leaf tightening means.
50. 15. A loose leaf binder comprising two binder members, leaf impaling means carried by the members, means for securing said binder members together, leaf tightening means for coöoperating with the edges of the 45 leaves adjacent the portions through which
- the impaling means extends, and a common operating member for the leaf tightening means and the means for securing the binder members together.
16. A loose leaf binder comprising two binder members, impaling pins carried by both of said members, a projection carried by one of the members, two clamping members mounted on the other member, one of said clamping members being fixed while the other is movable, said clamping members 55 engaging the projection on the other binder member to hold the two binder members together, a rotary shaft for effecting the operation of the movable clamping member, and leaf-tightening means for coöoperating with the edges of the leaves adjacent those portions through which the impaling projections pass, said leaf-tightening means being operated through the shaft which operates the movable clamping member. 60
17. A loose leaf binder comprising two binder members, impaling pins carried by both of said members, a projection carried by one of the members, two clamping members mounted on the other member, one of said clamping members being fixed while the other is movable, said clamping members 65 engaging the projection on the other binder member to hold the two binder members together, a rotary shaft for effecting the operation of the movable clamping member, leaf-tightening means for coöoperating with the edges of the leaves adjacent those portions through which the impaling projections pass, said leaf-tightening means being operated through the shaft which operates the movable clamping member. 70
18. A loose leaf binder comprising two separable binder members, leaf impaling means carried by the members, slotted wedge-shaped tightening devices movably mounted on one of said binder members and arranged to coöperate with the walls of notches formed in those edges of the leaves adjacent the portions penetrated by the impaling means, and projections mounted on the other of said binder members for engaging in the slots of said tightening devices, such tightening devices being substantially coextensive with the distance between the leaf-engaging faces of the binder members. 75
